[57] CLAIM

The ornamental design for an end closure for a container, substantially as shown and described.

DESCRIPTION

FIG. 1 is a top plan view of an end closure for a container showing my new design;

FIG. 2 is a sectional view taken along line 2—2 of FIG. 1;

FIG. 3 is a top plan view of a second embodiment of an end closure for a container showing my new design;

FIG. 4 is a sectional view taken along line 4—4 of FIG. 3; and

FIG. 5 is a sectional view taken along line 5—5 of FIG. 3.

FIG. 1

FIG. 3

FIG. 2

FIG. 4

FIG. 5
